SLIDING DRAWER ASSEMBLY

Harvey W. La Branche, James Charles Preble, and Bruce K. Boundy, Tacoma, Wash., assignors, by mesne assignments, to Ekco Products Company, Chicago, Ill., a corporation of Delaware

Filed Mar. 31, 1958, Ser. No. 725,106
3 Claims. (Cl. 312—348)

This invention relates to sliding drawer assemblies. It pertains particularly to assemblies including a plastic drawer intended for use in kitchen cabinet and like installations.

This application is a continuation in part of the application of J. Charles Preble, Serial No. 690,004, filed October 14, 1957, for Drawer Assembly.

While drawers made of plastic have many advantages which make them well suited for kitchen cabinet use, their application is attended by the disadvantage that they tend to break at the points of attachment to the various components of the drawer assembly. Also, it is difficult to integrate them into the assemblies conventionally employed in cabinet construction.

Accordingly the general object of the present invention is to provide a drawer assembly which may include a plastic drawer durably secured to the other components of the assembly.

It is another object of this invention to provide a drawer assembly which is rigid and strong even though it includes a plastic drawer of a flexible and somewhat frangible character.

It is another object of this invention to provide a drawer assembly which fits snugly into the drawer opening, yet operates easily without chatter.

It is another object of this invention to provide a drawer assembly which is provided with front and rear stops which limit the drawer travel and absorb the shock of opening and closing the drawer.

It is another object of this invention to provide a drawer assembly which is easily installed, and easily removed for cleaning.

It is another object of this invention to provide a drawer assembly which is versatile in that it may be installed in either standard or non-standard drawer openings of diverse depths and widths.

The manner in which the foregoing and other objects of this invention are accomplished will be apparent from the accompanying specification and claims considered together with the drawings, wherein like numerals of reference indicate like parts and wherein:

FIG. 1 is a plan view of the herein described sliding drawer assembly;

FIG. 2 is a sectional view, taken along line 2—2 of FIG. 1;

FIGS. 3 and 4 are detail sectional views taken along lines 3—3 and 4—4 of FIG. 1 respectively;

FIG. 5 is a detail sectional view taken along line 5—5 of FIG. 2;

FIG. 6 is a fragmentary sectional view similar to FIG. 5 but illustrating the application of the invention to assemblies including a wooden drawer; and

FIG. 7 is a plan view illustrating the manner in which the presently described drawer assembly may be used in drawer openings of non-standard width.

In the drawings, the numeral 10 indicates a drawer, preferably one made of molded plastic. The two longitudinal edges of the drawer are formed with integral, outwardly extending flanges 12, 14. The front wall is formed with a similar flange 16 and the rear wall with a flange 18. It is preferred to form these flanges as a continuous flange member extending outwardly from the entire periphery of the drawer in the manner illustrated.

2

A face panel 20 made from wood or other suitable material is dimensioned to overlie the front of the drawer. It may be of either the flush type or lip type, and is formed with a groove extending longitudinally along the upper part of its inner face. This groove is designed to receive flange 16.

The drawer assembly further includes a pair of slide members 22 of substantially identical construction and mounted one on each side of the drawer. In the illustrated form of the invention, each slide member comprises an elongated, reversely bent strip of metal dimensioned to receive and to be crimped over the side flanges of the drawer in the manner indicated particularly in FIG. 5. This affords a means for holding the slide member securely in place without the necessity of drilling or otherwise mutilating the flange of the drawer which, if the drawer be made of plastic, might be easily damaged by such a procedure.

As is shown particularly in FIG. 3, the slide members 20 are formed with integral downwardly bent tabs 24 which may be attached by screws or other suitable means to the inside face of face panel 20.

To assist in controlling the travel of the drawer in and out of the drawer opening, a block 26 of plastic or other suitable material is secured to the inner end of each of the slide members. The block preferably is formed with a slot dimensioned to receive the overlying, registering edges of the slide member and drawer in the manner illustrated in FIG. 4. Each block is formed with a projection 28 adapted to be inserted in a corresponding opening in the upper surface of slide member 22, thereby securing the block in place. Also, each block is formed with a beveled surface 30 to assist in introducing the drawer into the drawer opening.

Cooperating with slide members 22 are a pair of guide members or tracks 32. Each of these may be formed in three longitudinal sections: a ceiling section 34, a side wall section 36, and a floor section 38. A forward extension 40 and a rearward extension 42 are perforated and afford means of affixing the guide members to cabinet or frame members 44 (FIG. 1). It is to be noted that the rearward extension 42 is of substantial length so that it may be bent at right angles as shown in the latter figure. This makes possible adjusting the overall length of the guide by bending it at the appropriate place. It also makes possible fastening the guide securely since it may be attached to both the side frame member and the rear frame member which define the drawer opening.

Means are provided in the guide members for limiting the drawer travel both inwardly and outwardly. To this end there is provided a pocket 48 (FIG. 2) having a back wall 50. This pocket is dimensioned to receive block 26 which abuts against back wall 50 when the drawer is closed.

It is to be noted that in the closed position face panel 20 remains spaced slightly from the frame containing the drawer. As a consequence, block 26 absorbs the shock of closing and prevents the inertia of the drawer and its contents from tearing the drawer loose from the face panel.

The guide members also are provided with a second pocket 52 which, like pocket 48 is designed to accommodate block 26. A projection 54 is formed in the ceiling of the guide member directly above the pocket. This serves as an abutment or stop which engages the block during outward travel of the drawer, limiting its extension. Still, the drawer may be easily inserted and removed from the opening by tilting it at an angle at which block 26 traverses pocket 52 and then is elevated to a plane at which, on reverse motion, it will engage projection 54.

An angular pad 56 is mounted in the floor of guideway 32 near the outer end thereof. It engages the underside of slide 22 and maintains the slide level when it is in its

operative position. A knob 58 is provided on the face panel for the usual purpose.

The presently described assembly is adaptable for use not only with plastic drawers in the manner described above but also with the conventional wooden drawers. The manner in which this may be accomplished is illustrated in FIG. 6.

In accordance with this embodiment the wooden drawer 60 carries a longitudinal flange 62 which is analogous in function to the integral side flanges 12, 14 of the plastic drawer. Thus this flange mounts slide 22 which is in sliding engagement with pad 56 in guides 32.

Still further, the presently described assembly is adaptable for use in drawer openings of non-standard width. This feature of the invention is illustrated in FIG. 7.

In this embodiment guide members 64, which correspond in function to guide member 32 described above, are provided with forward and rearward extensions 66, 68, respectively. These may be bent as required to space the guide member inwardly from the frame member 44 to the extent required to locate the drawer properly.

Thus it will be apparent that by the present invention we have provided a drawer assembly which is particularly adaptable for use with plastic drawers, being designed to mount them in such a manner that they are not damaged during installation and use. Furthermore, the extent of drawer travel is limited to a practical working range without detracting from the ease with which the drawer may be inserted into and removed from the drawer opening, as required for installation and cleaning. Furthermore, the assembly accommodates drawers of non-standard size and makes possible their operation easily and without chatter.

It is to be understood that the form of our invention herewith shown and described, is to be taken as a preferred example of the same, and that various changes in the shape, size and arrangement of parts may be resorted to, without departing from the spirit of our invention or the scope of the subjoined claims.

Having thus described our invention we claim:

1. A drawer assembly comprising a drawer, a face panel, a pair of elongated slides affixed to the lateral sides of the drawer, a pair of elongated guides dimensioned to receive the slides, and means for affixing the guides in spaced apart relation to a stationary support on which the drawer assembly is to be mounted, at least one of the guides including integral ceiling, side wall and floor segments, the floor segment being formed with spaced central and rearward pockets, the rearward pocket terminating in a vertical abutment, the ceiling being formed with an integral abutment positioned above the central pocket, and the associated slide mounting a block dimensioned for reception in the central pocket and positioned for engagement with the abutment above the central pocket upon sliding movement of the drawer to its open position, said block being engageable with the rearward pocket vertical abutment in its closed position, the forward length of the

guide to said vertical abutment being less than the length of the drawer for limiting inward travel of the drawer to prevent abutment of the face panel.

2. A drawer assembly comprising a frangible drawer portion depending from an upper, outwardly projecting flange extending longitudinally along each side, a pair of elongated rigid slides, gripping means for affixing the slides one to each of the longitudinal flanges, a rigid face panel, means for affixing the forward ends of the slides to the face panel to form a rigid drawer supporting frame, a pair of elongated guides, at least one of the guides having a rearward pocket terminating in a vertical abutment and the associated slide mounting a block, said block being engageable with the rearward pocket vertical abutment in its closed position, the forward length of the guide to said vertical abutment being less than the length of the drawer for limiting inward travel of the drawer to prevent abutment of the face panel.

3. A drawer assembly comprising a frangible drawer portion depending from an upper, outwardly projecting flange extending longitudinally along each side, a pair of elongated rigid slides, gripping means for affixing the slides one to each of the longitudinal flanges, a rigid face panel, means for affixing the forward ends of the slides to the face panel to form a rigid drawer supporting frame, a pair of elongated guides dimensioned to receive the slides, at least one of the guides including integral ceiling, side wall and floor segments, the floor segment being formed with spaced central and rearward pockets, the rearward pocket terminating in a vertical abutment, the ceiling being formed with an integral abutment positioned above the central pocket, and the associated slide mounting a block dimensioned for reception in the central pocket and positioned for engagement with the abutment above the central pocket upon sliding movement of the drawer to its open position, said block being engageable with the rearward pocket vertical abutment in its closed position, the forward length of the guide to said vertical abutment being less than the length of the drawer for limiting inward travel of the drawer to prevent abutment of the face panel.
